UNITED STATES PATENT OFFICE.

WALTER REICHSTEIN, OF BERLIN, GERMANY.

SAFETY PADLOCK.

1,420,578.

Specification of Letters Patent. Patented June 20, 1922.

Application filed January 12, 1922. Serial No. 528,605.

To all whom it may concern:

Be it known that I, WALTER REICHSTEIN, a citizen of the German Republic, residing at Berlin, Germany, have invented certain new and useful Improvements in Safety Padlocks, of which the following is a specification.

This invention relates to a safety padlock with ring-shaped tumblers. According to 10 this invention the tumbler rings are mounted upon a guide cylinder so that they can be turned between two fixed discs, said tumbler rings being designed to act upon a bow-shaped shackle which, after its two arms 15 have been inserted into the padlock, is locked in position through the rotation of said tumbler rings.

Owing to this construction a strong padlock is produced which is nevertheless not 20 heavy because all the principal parts of the padlock can be made by pressing or stamping. Upon the circumference of the fixed discs as well as upon that of the movable discs characters, figures or signs are marked, 25 preferably figures from 0 to 9, so that the proper position of the discs can be indicated by a number, or by a word. Any of the figures marked on the discs can be chosen as a mark for the adjustment of the discs 30 to a position in which the lock may be opened, so that it is impossible to discover the number which permits opening of the padlock.

This improved padlock presents further 35 the advantage that it can not be opened by an unauthorized person, either mechanically or through adjustment of the rings. Owing to the fact that the shackle is made in one part and because the two arms of this 40 shackle penetrate into the body of the padlock it would require far too much time to break the padlock open.

In the drawings:

Fig. 1 is a side elevation of the improved 45 padlock;

Fig. 2 is a vertical section of the same;

Fig. 3 is a sectional view of a tumbler 50 ring;

Fig. 4 is a plan view of the same;

Fig. 5 is a vertical sectional view of the 55 inner part of the padlock casing; and

Fig. 6 is a plan view of the same.

The body of the padlock consists of two 60 fixed discs *a* which are connected by means of a bolt *b* and which enclose a guide sleeve *c* having a vertical groove *d*. The tumbler 65

rings *f* are revolvably mounted upon said guide sleeve *c* and are of angular cross section, each ring having in the inwardly projecting flange a semi-circular notch *g*, 70 the notches of all the tumbler rings forming with the groove *d* of the guide sleeve a channel for the reception of one of the arms of the bow-shaped shackle *h*. This arm of the shackle *h* has notches *i* designed 75 to receive the tumbler rings *f*. The other arm of the shackle is not locked by the tumbler rings but merely inserted through registering holes of the fixed discs *a* and of the guide sleeve *c*. The shackle *h* is 80 locked in the padlock through the medium of the tumbler rings and it can be removed only when all the rings *f* have been adjusted so that their notches *g* register with the notched arm of the shackle.

Upon the circumference of the fixed discs *a* and of the tubular rings *f* figures from 0 to 9 are marked, the figures in vertical direction forming a number, the first and last figure of which are fixed, all the intermediate figures being adjustable. As any of the 85 numbers capable of being formed by the figures can be used as a predetermined mark for opening the lock, a great variety of combinations is possible so that for any unauthorized person it is impossible to find out the correct number.

I claim:

A safety padlock comprising a fixed upper disc having a pair of apertures, a fixed 90 lower disc having a single aperture, both of said discs having predetermined symbols produced upon their peripheries, a bolt riveted in said discs and connecting the same in spaced relation, a cylindrical guide sleeve located between said discs and having a groove 95 of semi-circular cross section extending lengthwise thereof, said sleeve having an aperture in registry with one of the apertures of said upper disc and with the aperture of said lower disc, tumbler rings having peripheral flanges and inwardly extending flanges, the latter being rotatably mounted upon said sleeve and having inwardly open semicircular notches adapted to register 100 with each other in the axial direction of the lock and with the groove of said sleeve transversely of said lock to form an interior channel, said peripheral flanges having predetermined symbols produced thereon for 105 co-operation with each other and with the symbols of said upper and lower discs to 110

form a predetermined combination and a bow-shaped shackle having two arms, one of which is arranged to be inserted through said registering apertures within said sleeve 5 and the other of which is arranged to be inserted through the other aperture of said top disc into said interior channel, said last-named arm having a series of spaced notches for receiving the inwardly extending

flanges of said tumbler rings to lock said 10 shackle in said padlock.

In testimony whereof I affix my signature in presence of two witnesses.

WALTER REICHSTEIN.
